UNITED STATES PATENT OFFICE

KIRK D. SMITH, OF NEWPORT, NEW HAMPSHIRE.

WATER-WHEEL.

1,073,824.

Specification of Letters Patent. Patented Sept. 23, 1913.

Application filed September 24, 1912. Serial No. 722,014.

To all whom it may concern:

Be it known that I, KIRK D. SMITH, a citizen of the United States, residing at Newport, in the county of Sullivan and 5 State of New Hampshire, have invented certain new and useful Improvements in Water-Wheels, of which the following is a specification.

This invention has relation to water 10 wheels and has for its object to provide a wheel of simple structure which may be used to advantage for developing a maximum amount of power when subjected to the weight or force of water in motion.

15 With the above object in view the wheel consists of a shaft upon which is mounted a series of disks. Buckets of peculiar configuration are located between the disks and the disks are provided with openings whereby 20 the water may pass from one bucket to the next adjacent bucket throughout the series of buckets so that the water may move in a general direction longitudinally with the shaft as the wheel rotates.

25 Means may be provided for driving the water in streams into the bucket and a hood or other means may be provided at one side of the wheel for holding the water in the buckets.

30 With these and other objects in view, the invention consists in certain novel features of construction as hereinafter shown and described, and then particularly pointed out in the claims and in the drawings illustrative of the preferred embodiment of the 35 invention.

Figure 1 is a side view of the water wheel with parts in section. Fig. 2 is an end view of the same. Fig. 3 is a transverse sectional view of the same. Fig. 4 is a vertical sectional view at one end of the same. Fig. 5 is a plan view of a modified form of pocket member which may be used in the wheel.

40 Corresponding and like parts are referred 45 to in the following description and indicated in all the views of the accompanying drawings by the same reference characters.

The water wheel comprises a shaft 1 which is journaled in suitable bearing in 50 any appropriate manner. Disks 2 are mounted upon the shaft 1 and all of the disks except one of the terminal disks are provided with openings 3. These openings are inclined at acute angles to the planes of 55 the disks as best illustrated in Fig. 4 of the drawing. Blocks 4 are mounted upon the

shaft 1 between the disks 2 and the said blocks are provided in their opposite side edges with recesses 5 which constitute buckets. The ends of the openings 3 are located 60 in the sides of the disks 2 approximately at the receiving ends of the recesses 5. The recesses 5 may be generally V-shaped as shown in Fig. 3 or the said recesses may be approximately scroll-shaped as shown in Fig. 65 5. The recesses 5 in each block are located at equal distances from the center of the block. The outer edges of the blocks are arcuate and the outer walls of the recesses 5 terminate at the ends of the arcuate edges 70 of the blocks and form comparatively sharp edges 6.

The water for turning the wheel may be applied to the same in any desired manner, but in Fig. 1 a method of applying water is 75 illustrated as an example. A pipe 7 extends along the length of the wheel and the said pipe is provided with discharging nozzles 8 which are located opposite the blocks 4. A hood 9 surrounds the wheel and is located in 80 such close proximity to the same that the water which is discharged from the nozzles 8 is retained in the recesses 5 by the hood as the said recesses describe approximately one-half of a revolution about the axis of a 85 shaft 1.

The edges 6 of the blocks 4 are in stepped relation throughout the length of the wheel. Consequently the recesses 5 are not directly 90 opposite each other at the opposite sides of the disks 2. Therefore it is necessary to slant the openings 3 in order that the water may pass through the disks from the recesses of one block to the recesses of the next adjacent block and enter the recesses of the 95 succeeding blocks at proper points.

Operation of the wheel is as follows: The water is permitted to flow or is forced into the recesses 5 and the weight of the water in the recesses at the upper part of the wheel 100 will cause the said wheel to turn upon the said shaft 1. Through this turning movement the hood 9 retains the water in the recesses. When the edges 6 of the recesses which contain the water arrive at the lowest point of the wheel the water flows by gravity out of the recesses, and thus the wheel is maintained heavy at one side of the shaft 2 and light at the other side. Through the rotation of the wheel as above 105 described the water may flow from one recess through the openings 3 into the recess

of the next adjacent block 4 and this movement of the water is continued throughout the succeeding blocks and recesses of the series. Therefore as the water travels around 5 the axis of the shaft 1 it also moves in a direction longitudinal of the shaft and this economizes the water and facilitates the rotation of the water of the wheel.

Having described the invention what I 10 claim is:

1. A water wheel comprising a shaft, disks located upon the shaft, blocks located between the disks and having recesses, said disks having openings which communicate 15 with the recesses in the blocks and at the opposite sides of the disks.

2. A water wheel comprising a shaft, disks mounted thereon, blocks located between the disks and having recesses, said recesses being 20 in stepped relation throughout the length of the wheel, the disks having openings, the ends of which communicate with the recesses of the blocks at the opposite sides of the disks.

25 3. A water wheel comprising a shaft, disks mounted thereon, blocks mounted upon the shaft and located between the disks, said blocks having at their opposite edges recesses located at equal distances from the 30 centers of the blocks, said disks having open-

ings, the ends of which communicate with the recesses of the blocks at the opposite sides of the disks.

4. A water wheel comprising a shaft, disks mounted upon the shaft, blocks located between the disks and having in their edges recesses, the side walls of which converge to the ends of the blocks forming comparatively sharp edges, said disks having openings, the ends of which communicate with 35 the recesses located in the blocks at the opposite sides of the disks.

5. A water wheel comprising a shaft, disks located thereon, blocks mounted upon the shaft between the disks and having recesses, 40 said disks having openings, the ends of which communicate with recesses of the blocks at the opposite sides of the disks, a hood located adjacent the wheel in close proximity to the periphery of the same and 45 discharge nozzles having their outer ends directly toward the blocks and recesses therein.

In testimony whereof I have affixed my signature in presence of two witnesses.

KIRK D. SMITH.
